UNITED STATES PATENT OFFICE.

THEODORE C. HOOK, OF PHILADELPHIA, PENNSYLVANIA.

STAMP OR LABEL AFFIXING MACHINE.

No. 857,625.

Specification of Letters Patent.

Patented June 25, 1907.

Application filed May 10, 1905. Renewed April 23, 1907. Serial No. 369,763.

To all whom it may concern:

Be it known that I, THEODORE C. HOOK, a citizen of the United States, residing at Philadelphia, county of Philadelphia, and State of Pennsylvania, have invented a certain new and useful Improvement in Stamp or Label Affixing Machines, of which the following is a specification.

My invention relates to a new and useful improvement in stamp or label affixing machine, and has for its object to provide a device in which a number of stamps or labels will be held in the machine, one piled upon top of the other with the gum surface downward, and by first pressing the machine upon a damp surface so as to dampen the gum upon the lowermost stamp or label, and then by pressing downward upon a plunger the lowermost stamp or label will be affixed to the surface upon which it is pressed.

With these ends in view, this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawing forming a part of this specification, in which—

Figure 1 is a vertical longitudinal section through my improved device; Fig. 2, a side elevation of the lower part of the device; Fig. 3, a bottom plan view of the device.

A represents the body portion, which is open at the lower end, and in the lower end is adapted to be inserted the gummed stamps or labels B with the gum surface downward.

C is a plate adapted to slide in the body portion and rest upon the top of the stamps or labels, and above this plate is a light spring D interposed between the plate C and the upper portion of the body, said spring tending to press the plate C downward upon the stamps or labels.

E is a plunger adapted to slide vertically and centrally in the body portion and extend from the upper end thereof, the lower end of the plunger is provided with an enlargement E', and a spring F surrounds the plunger and is interposed between the body A and a head G formed upon the upper end of the plunger. This spring F tends to force the plunger upward and hold the enlargement E' normally

against the lower end of a neck A' formed with the body portion and extending downward into the hollow portion thereof, thus the lower end of the plunger will normally be held from out of contact with the plate C.

Upon each side of the body portion are arranged the spring strips H, the lower ends of which are bent around underneath and normally extend a short distance inside of the opening of the body portion, as shown in Figs. 1 and 3. These spring strips H normally tend to spring away from the body portion so as to remove the protruding ends H' from underneath the stamps, but the ends H' are held underneath the stamps by means of a ring I surrounding the body portion and the spring strips H, so that when the ring I is forced downward to its lowermost position, as shown in Figs. 1 and 2, it will force the spring strips H toward the body portion, and therefore cause the ends H' to protrude underneath the stamps or labels. These ends prevent the stamps or labels from falling outward from the machine.

In operation the device is first lightly pressed upon a moistened surface so as to moisten the lowermost stamp or label, and then by placing the machine upon the surface to which the stamp or label is to be affixed and pressing downward upon the plunger E until it comes in contact with the plate C pressure is thus exerted to affix the lowermost stamp or label to the surface, and when the machine is raised this stamp or label will adhere to the surface, and the edges will pass the protruding ends H' of the spring strips. This operation can be repeated as many times as there are stamps or labels in the machine.

When it is desired to fill the magazine of the machine the ring I is raised so as to allow the spring strips to spring away from the body portion, and then the opening of the body portion is free for the insertion of the stamps or labels.

Of course I do not wish to be limited in construction or position of the said machine, as it can be used in a horizontal position for affixing stamps or labels to boxes of all kinds without departing from the spirit of my invention.

Having thus fully described my invention, what I claim as new and useful, is—

1. In a device of the character described, a body portion provided with a recess opening upward from the lower end thereof, the

- stamps or labels adapted to be piled one on top of the other in the lower end of the body portion with the blank side downward, thin strips adapted to protrude beyond the inside edge of the recess in the body portion at several points so as to lie underneath the edge of the lowermost stamp or label and prevent the accidental displacement of said stamps or labels, means for removing said strips outward when the machine is to be filled, a plate resting upon the top of the stamps or labels and adapted to slide in the recess of the body portion, a spring interposed between said plate and the body portion, a vertically sliding plunger arranged to slide in the body portion above the plate, a spring tending to force the plunger upward, the lower end of the plunger normally held out of contact with the plate but adapted to come in contact with the plate when the plunger is forced downward, as and for the purpose specified.
2. In a device of the character described, a body portion provided with a vertical recess formed upward from the lower end thereof, the stamps or labels adapted to be placed one above the other with the blank side downward in the lower end of the recess, spring strips arranged upon opposite sides of the body portion upon the outside thereof, said spring strips bent at their lower ends so as to extend underneath the body portion and normally protrude a slight distance beyond the recess so as to lie underneath the edges of the stamps, a ring encircling the body portion and spring strips, said ring adapted to hold the spring strips in their normal position when it is down in its lowermost position, the spring strips adapted to move away from the body portion when the ring is raised, a plate arranged upon the top of the stamps or labels and adapted to slide within the recess, a spring interposed between said plate and the upper end of the body portion, a vertically sliding plunger arranged in the body portion above the plate, an enlargement formed upon the lower end of the body portion, a head formed upon the upper end of the plunger, a spring interposed between the body portion and the head, said spring adapted to normally hold the enlargement against the body portion and at a distance above the plate, as and for the purpose specified.
3. In testimony whereof, I have hereunto affixed my signature in the presence of two subscribing witnesses.
